BY
Thomas R. Haney
ATTORNEY.

UNITED STATES PATENT OFFICE.

JOHN HENRY ROSEMEYER, OF ELMIRA, IDAHO.

CABLE OR ROPE CONNECTOR OR ANCHOR.

1,385,645.

Specification of Letters Patent. Patented July 26, 1921.

Application filed December 9, 1920. Serial No. 429,414.

To all whom it may concern:

Be it known that I, JOHN H. ROSEMEYER, a citizen of the United States of America, residing at Elmira, in the county of Bonner 5 and State of Idaho, have invented certain new and useful Improvements in Cable or Rope Connectors or Anchors, of which the following is a specification.

My present invention relates generally to 10 cable or rope connectors or anchors, and more particularly to what is commonly known as a cable hitch, my object being the provision of a one piece construction providing for an effective cable or rope grip and which will, 15 at the same time be strong and durable under constant severe usage.

In the accompanying drawing illustrating my present invention and forming a part of this specification,

20 Figure 1 is a top plan view of my improved cable hitch,

Fig. 2 is a side elevation,

Fig. 3 is a central longitudinal section,

Fig. 4 is a cross section, and,

25 Fig. 5 is a diagram of a cable coiled as it is in connected relation around my improved grip.

The cable grip proposed by my present invention has an oval shaped body 10 which 30 may be either solid or in the form of a ring as shown so that its connection with other or adjacent parts may be accomplished either by an external projection 11 of the body pivotally connected as at 12 to such adjacent 35 part 13, or by a hook (not shown) carried by such adjacent part and passed through the ring-shaped body.

The body 10 has a peripheral groove 15 which receives a loop 16 of the cable 17 to 40 be gripped, the loop being formed as seen in Fig. 5 in overlying relation to the free end 18 of the cable.

In addition to its peripheral groove 15, the body 10 has a transverse groove 19 adja- 45 cent to one end, the ends of which transverse groove open into the peripheral groove to

the full depth of the latter only so as to thus receive the cable end 18 in such manner that it is tightly engaged and frictionally held by those portions of the cable loop 16 at the 50 opposite ends of the transverse groove 19.

It is thus obvious that my improved construction provides for a double grip on the free end of the cable by portions of the cable loop in the peripheral groove against which 55 pressure is exerted in use in relatively opposite directions so that a tight effective holding will be promoted and brought about.

It is also obvious that I do this by an integral one-piece construction which will be 60 strong and durable in the constant severe use to which articles of this character are subjected, as well as one whose functions and effectiveness will not be curtailed in any way by rust or other direct or indirect causes of 65 weather.

I claim:

1. A cable hitch comprising an integral one piece body having a single peripheral and continuous groove and also having a 70 transverse surface groove thereacross whose ends communicate with spaced portions of the peripheral groove, whereby the free end of a cable traversing the transverse groove will be gripped at opposite ends of the said 75 groove by the coil of a cable disposed completely around in the peripheral groove.

2. A cable hitch having its body of ring shape and oval form and provided with a single peripheral groove continuously there- 80 around to receive the coil of a cable and with a transverse groove adjacent to one end to receive the terminal portion of the cable coil, the ends of said transverse groove communicating at spaced points with the peripheral 85 groove whereby the opposite end of said terminal portion of the cable in the transverse groove will be gripped by the coil in the peripheral groove.

In testimony whereof I have affixed my 90 signature.

JOHN HENRY ROSEMEYER.
